UNWINDING MACHINE

Herman Walter Gilbert, Kew Gardens, N. Y., assignor to Cutting Room Appliances Corp., New York, N. Y., a corporation of New York

Application October 2, 1940, Serial No. 359,352

14 Claims. (Cl. 242—68)

This invention relates to new and useful improvements in unwinding machines. This application is a continuation-in-part of my Patent No. 2,220,230, granted on November 5, 1940, for an unwinding machine.

This invention proposes an unwinding machine which is characterized by a pair of spaced side supports for resting on a counter, table or the like and having semi-circular top edges, and connected together in a unit with several tubes, and supporting end wall members in a certain way, which in turn are arranged to support a rod for supporting a roll of cloth.

More specifically the invention proposes to provide each end wall member with connector rods which extend into the tubes joining together the side supports in a certain way, so that the unwinding machine may be extended or contracted as desired, to accommodate rolls of cloth of different widths.

Still further the invention proposes to mount the rod for supporting the roll of cloth, in a certain way upon the end wall members, which way is characterized by the fact that the rod may be disengaged from one of the end wall members and then swung forwards or rearwards so that the roll of cloth may be conveniently mounted thereon and removed as desired.

Another object of the invention resides in the novel arrangement by which the connector rods may be clamped in various extended positions from the tubes to fix the width of the unwinding machine to a size best capable of accommodating a roll of cloth of a specific width.

As another object of this invention it is proposed to provide means for holding the connector rods in their fully extended positions to prevent their complete disengagement from the tubes when the unwinding machine is extended to its full width.

Still further the invention proposes the construction of an unwinding machine as mentioned which is simple and durable and which may be manufactured and sold at a reasonable cost.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure—

Fig. 1 is a front elevational view of an unwinding machine constructed in accordance with this invention.

Fig. 2 is an end elevational view of Fig. 1 looking in the direction of line 2—2 thereof.

Fig. 3 is an end elevational view of Fig. 1 looking in the direction of the line 3—3 thereof.

Fig. 4 is a fragmentary enlarged sectional view taken on the line 4—4 of Fig. 1.

Fig. 5 is a perspective view of a certain U-shaped member used in the device.

Fig. 6 is a fragmentary front elevational view of an unwinding machine constructed in accordance with another form of this invention.

Fig. 7 is a fragmentary enlarged horizontal sectional view taken on the line 7—7 of Fig. 6.

Fig. 8 is a sectional view similar to Fig. 7 but illustrating the parts in a different position.

Fig. 9 is a fragmentary sectional view taken on the line 9—9 of Fig. 7.

Fig. 10 is a fragmentary enlarged vertical sectional view taken on the line 10—10 of Fig. 6.

Fig. 11 is a fragmentary vertical sectional view taken on the line 11—11 of Fig. 10.

Fig. 12 is a fragmentary enlarged end elevational view looking in the direction of the line 12—12 of Fig. 6.

Fig. 13 is a fragmentary vertical sectional view taken on the line 13—13 of Fig. 12.

Fig. 14 is a fragmentary vertical sectional view taken on the line 14—14 of Fig. 13.

The unwinding machine in accordance with this invention includes a pair of spaced side supports 10 for resting on a counter, table or the like and having semiannular top edges 10a. Tubes 11 are mounted between the said side supports 10 for holding them fixedly relative to each other. Each of the side supports 10 is provided with several bushing portions 10b through which the tubes 11 extend. The end of each of the tubes is formed with threads 12. Nuts 13 are threadedly mounted on these threads 12 and are disposed on opposite sides of the said side supports 10 and serve to fixedly connect the tubes 11 with the said supports.

End wall members 14 and 15 extend forwards and rearwards, and are disposed outwards of the outer faces of the said side supports 10. Connector rods 16 are mounted on the end wall members 14 and 15 and slidably engage in the tubes 11 for movably connecting the end wall members 14 and 15 with the said side supports 10.

The end wall member 14 has a vertical central portion 14a, and two downwardly and outwardly extending arm portions 14b. These portions are formed with flanged edges to stiffen them. The rods 16 are connected with the end wall member 14 by engaging through portions

thereof. Nuts 18 threadedly engage the end portions of the rods 16 and abut the opposite faces of the end wall members for fixedly connecting the rods thereon. The top end of the central portion 14a of the end wall member 14 is formed with a U-shaped element 14c. The bottom end of the central portion 14a rests upon the supporting counter, table or the like.

The end wall member 15 has a vertical central portion 15a which is provided with an arcuate bottom portion 15aa having a pair of legs 15' adapted to rest on the counter, table or the like for assisting in supporting the unwinding machine. The said spaced side supports 10 are formed with similar leg portions 15' which are also adapted to rest on the counter, table or the like for supporting the unwinding machine. The end wall member 15 is also provided with a pair of downwardly and outwardly extending arm portions 15b which connect with the ends of the arcuate bottom portion 15aa. The member 15 has edge flanges for stiffening purposes. The rods 16 are mounted upon the end wall member 15 in a way similar to the connection between the rods 16 and the end wall member 14, previously described. Nuts 18 are threadedly mounted upon the rods 16 and engage opposite faces of the end wall member 15 for accomplishing the connection of these parts.

The top end of the central portion 15a is provided with an inwardly directed offset end portion 15c upon which the U-shaped member 20 is swively mounted. This U-shaped member 20 is provided with a pair of upwardly and outwardly extending top faces 20a arranged on the tops of the arms thereof and adapted to guide a rod which is rested thereon to a position in between the arms of the U-shaped member. A stud 21 projects from the bottom of the U-shaped member 20 and engages through a complementary opening formed in the offset portion 15c. A cotter pin 22 removably engages through the bottom of the stud 21, see Fig. 3, and removably holds the U-shaped member 20 in position. A rod 23 for supporting a roll of cloth is rested across the U-shaped parts 20 and 14c.

The rod 23 is provided with the usual blade 24 for engaging into the end of a roll of cloth for non-rotatively securing the roll upon the rod. The rod 23 is also provided with a reduced section 23a which is extended into the U-shaped portion 14c to rotatively connect the rod 23 with the end wall member 14. The end of the rod 23 adjacent the reduced portion 23a is provided with a handle 25 by which it may be conveniently gripped and turned when desired. The dot and dash lines 26 schematically illustrate a roll of cloth mounted on the rod 23.

Means is provided for fixedly holding said connector rods 16 in various positions extended from the tubes 11. This means comprises wing screws 28 threadedly engaged through the bosses 19b of the said side supports 10 and through the tubes 11 and abutting the rods 16. These wing screws may be loosened to free the rods 16 and then the latter may be extended, or retracted as desired. The wing screws 28 may then be turned inwards to clamp the rods in their new positions.

In Figs. 6 to 9 inclusive, a modified form of the invention has been disclosed which distinguishes from the prior form in the fact that means has been provided for holding the connector rods 16' in their fully extended positions in a way so that they will not disengage from the side supports 10. This means includes recessed portions 16a formed

immediately adjacent the inner end portions of the rods 16'. Each recessed portion has a right angle shoulder 16aa and a tapered shank portion 16ab. The nuts 13' which engage upon the outer ends of the tubes 11 are of extra length, and are provided with end wall portions 13a which have internal circular recesses 30. A leaf spring 31 is mounted in each recess 30. These leaf springs are fixedly supported at one of their ends by fastening elements 32 engaged through the leaf springs and connecting with the material of the nut 13'. Each leaf spring 31 supports a key block 33. Each key block 33 normally rests against the side of a rod 16', as illustrated in Fig. 7. However, when the rod 16' is fully extended the key block 33 rides down the tapered side portion 16ab of the recessed portion 16a and engages the shoulder 16aa as illustrated in Fig. 8 locking the rod against further extension.

Each nut 13' is provided with an opening 34 in its end wall which is aligned with an aperture 35 in the key block 33. The arrangement is such that an implement such as a nail may be inserted through the slot 34 and into the aperture 35 and then the key block 33 may be moved outwards against the action of the spring 31 to free the rod 16'. Then the rod 16' is free to be completely disengaged from the tube 11. When the parts are in the position illustrated in Fig. 8, the rod 16' is free to be moved inwards. It is only locked against outward extension.

A ball bearing 40 is fixedly mounted upon the rod 23 near the handle end 25. This ball bearing comprises an inner ball bearing race 40a, which is sweated on or in any other way fixedly attached on the rod 23, the usual ball cage and balls 40b, and the outer race 40c. This outer race 40c is adapted to slip into a groove 41 formed upon the inner face of the U-shaped element 14c. The groove 41 holds the ball bearing 40 from shifting laterally on the end wall 14. The U-shaped member 20 is formed with a dovetailed groove 42 formed along the inner face of the U-shaped at the top thereof. The ends of the groove 42 are closed with stationary blocks 43 which are frictionally engaged therein or held fixedly in any other manner. A plurality of steel balls 44 extend along the complete length of the remaining portion of the groove 42. The rod 23 is adapted to rest on the balls 44 which produce an excellent bearing for the rod 23, and thus for the roll of woolen goods, or other goods 26.

The operation of the unwinding machine is as follows:

An operator may stand at the left hand side of the machine as illustrated in Fig. 1, and may grip the handle 25 and lift the rod 23 out from the U-shaped element 14c. The rod 23 may now be swung forwards or rearwards. The U-shaped member 20 merely swivels on the stud 21. The rod 23 may be lifted off of the unwinding machine. It may be passed through a roll of cloth. Then the roll of cloth with the rod may be engaged on the machine by dropping the remote end of the rod 23 upon the U-shaped member 20. It will strike one part or the other of the upwardly and outwardly extending top faces 20a and will slip down into the base of the U-shaped member 20. Then the rod 23 may be moved around laterally so that the recessed portion 23a is superimposed above the U-shaped element 14c. It may then be let down into the element. The roll of cloth may now be conveniently unwound.

The unwinding machine may be adjusted to guide rolls of different widths merely by loosening the wing screws 28. Then the end wall members 14 and 15 may be moved inwards or outwards to adjust the width of the unwinding machine to the desired width. The screws 28 are then tightened to hold the new adjustment.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new and desire to secure by United States Letters Patent is:

1. An unwinding machine, comprising a pair of spaced side supports for resting on a counter, table or the like and having semi-annular top edges, tubes mounted between said side supports for holding them fixedly relative to each other, end wall members extending forwards and rearwards and disposed outwards of the outer faces of said side supports, connector rods mounted on said end wall members and slidably engaging in said tubes for movably connecting the end wall members with said side supports, a U-shaped element centrally on the top of one of said end wall members, a U-shaped member centrally and swivelly mounted on the top of the other of said end wall members, and a rod for supporting a roll of cloth rested across said U-shaped parts.

2. An unwinding machine, comprising a pair of spaced side supports for resting on a counter, table, or the like and having semi-annular top edges, tubes mounted between said side supports for holding them fixedly relative to each other, end wall members extending forwards and rearwards and disposed outwards of the outer faces of said side supports, connector rods mounted on said end wall members and slidably engaging in said tubes for movably connecting the end wall members with said side supports, a U-shaped element centrally on the top of one of said end wall members, a U-shaped member centrally mounted on the top of the other of said end wall members, and a rod for supporting a roll of cloth rested across said U-shaped parts, said side supports being provided with feet on which the unwinding machine may rest on said counter, table or the like.

3. An unwinding machine, comprising a pair of spaced side supports for resting on a counter, table or the like and having semi-annular top edges, tubes mounted between said side supports for holding them fixedly relative to each other, end wall members extending forwards and rearwards and disposed outwards of the outer faces of said side supports, connector rods mounted on said end wall members and slidably engaging in said tubes for movably connecting the end wall members with said side supports, a U-shaped element centrally on the top of one of said end wall members, a U-shaped member centrally mounted on the top of the other of said end wall members, and a rod for supporting a roll of cloth rested across said U-shaped parts, said side supports being provided with feet on which the unwinding machine may rest on said counter, table or the like, one of said end wall members being provided with similar feet to assist in supporting the unwinding machine.

4. An unwinding machine, comprising a pair of spaced side supports for resting on a counter,

table or the like and having semi-annular top edges, tubes mounted between said side supports for holding them fixedly relative to each other, end wall members extending forwards and rearwards and disposed outwards of the outer faces of said side supports, connector rods mounted on said end wall members and slidably engaging in said tubes for movably connecting the end wall members with said side supports, a U-shaped element centrally on the top of one of said end wall members, a U-shaped member centrally mounted on the top of the other of said end wall members, and a rod for supporting a roll of cloth rested across said U-shaped parts, the end of said tubes being engaged through said side supports, and nuts being threadedly mounted upon said end portions and engaging opposite faces of said side supports for connecting these parts together.

5. An unwinding machine, comprising a pair of spaced side supports for resting on a counter, table or the like and having semi-annular top edges, tubes mounted between said side supports for holding them fixedly relative to each other, end wall members extending forwards and rearwards and disposed outwards of the outer faces of said side supports, connector rods mounted on said end wall members and slidably engaging in said tubes for movably connecting the end wall members with said side supports, a U-shaped element centrally on the top of one of said end wall members, a U-shaped member centrally mounted on the top of the other of said end wall members, and a rod for supporting a roll of cloth rested across said U-shaped parts, said connector rods being engaged through openings in said end wall members, and nuts being threadedly mounted upon the end portions of said rods for securing these parts together.

6. An unwinding machine, comprising a pair of spaced side supports for resting on a counter, table or the like and having semi-annular top edges, tubes mounted between said side supports for holding them fixedly relative to each other, end wall members extending forwards and rearwards and disposed outwards of the outer faces of said side supports, connector rods mounted on said end wall members and slidably engaging in said tubes for movably connecting the end wall members with said side supports, a U-shaped element centrally on the top of one of said end wall members, a U-shaped member centrally and swivelly mounted on the top of the other of said end wall members, and a rod for supporting a roll of cloth rested across said U-shaped parts, said U-shaped elements being integral with its associated end wall member.

7. An unwinding machine, comprising a pair of spaced side supports for resting on a counter, table or the like and having semi-annular top edges, tubes mounted between said side supports for holding them fixedly relative to each other, end wall members extending forwards and rearwards and disposed outwards of the outer faces of said side supports, connector rods mounted on said end wall members and slidably engaging in said tubes for movably connecting the end wall members with said side supports, a U-shaped element centrally on the top of one of said end wall members, a U-shaped member centrally and swivelly mounted on the top of the other of said end wall members, and a rod for supporting a roll of cloth rested across said U-shaped parts, said U-shaped member having a stud engaging through an offset top portion of the associated

end wall member by which the U-shaped member is swivelly mounted.

8. An unwinding machine, comprising a pair of spaced side supports for resting on a counter, table or the like and having semi-annular top edges, tubes mounted between said side supports for holding them fixedly relative to each other, end wall members extending forwards and rearwards and disposed outwards of the outer faces of said side supports, connector rods mounted on said end wall members and slidably engaging in said tubes for movably connecting the end wall members with said side supports, a U-shaped element centrally on the top of one of said end wall members, a U-shaped member centrally and swivelly mounted on the top of the other of said end wall members, and a rod for supporting a roll of cloth rested across said U-shaped parts, said U-shaped member being provided with upwardly and outwardly extending top faces on the tops of the arms thereof for guiding the end of said rod into position between the arms of the U-shaped member.

9. An unwinding machine, comprising a pair of spaced side supports for resting on a counter, table or the like and having semi-annular top edges, tubes mounted between said side supports for holding them fixedly relative to each other, end wall members extending forwards and rearwards and disposed outwards of the outer faces of said side supports, connector rods mounted on said end wall members and slidably engaging in said tubes for movably connecting the end wall members with said side supports, a U-shaped element centrally on the top of one of said end wall members, a U-shaped member centrally mounted on the top of the other of said end wall members, a rod for supporting a roll of cloth rested across said U-shaped parts, and means for fixedly holding said connector rods in various positions extending from said tubes.

10. An unwinding machine comprising a pair of spaced side supports for resting on a counter, table or the like and having semi-annular top edges, tubes mounted between said side supports for holding them fixedly relative to each other, end wall members extending forwards and rearwards and disposed outwards of the outer faces of said side supports, connector rods mounted on said end wall members and slidably engaging in said tubes for movably connecting the end wall members with said side supports, a U-shaped element centrally on the top of one of said end wall members, a U-shaped member centrally mounted on the top of the other of said end wall members, a rod for supporting a roll of cloth rested across said U-shaped parts, and means for fixedly holding said connector rods in various positions extending from said tubes, comprising screws threadedly mounted through portions of said end wall members and said tubes and abutting said connector rods.

11. An unwinding machine, comprising a pair of spaced side supports for resting on a counter, table or the like and having semi-annular top edges, tubes mounted between said side supports for holding them fixedly relative to each other, end wall members extending forwards and rearwards and disposed outwards of the outer faces of said side supports, connector rods mounted on said end wall members and slidably engaging in said tubes for movably connecting the end wall members with said side supports, a U-shaped element centrally on the top of one of said end wall members, a U-shaped member centrally

mounted on the top of the other of said end wall members, a rod for supporting a roll of cloth rested across said U-shaped parts, and means for holding said connector rods in their fully extended positions from disengaging said side supports.

12. An unwinding machine, comprising a pair of spaced side supports for resting on a counter, table or the like and having semi-annular top edges, tubes mounted between said side supports for holding them fixedly relative to each other, end wall members extending forwards and rearwards and disposed outwards of the outer faces of said side supports, connector rods mounted on said end wall members and slidably engaging in said tubes for movably connecting the end wall members with said side supports, a U-shaped element centrally on the top of one of said end wall members, a U-shaped member centrally mounted on the top of the other of said end wall members, a rod for supporting a roll of cloth rested across said U-shaped parts, and means for holding said connector rods in their fully extended positions from disengaging said side supports, comprising key blocks resiliently urged against the sides of said connector rods, and recessed portions upon the inner ends of said connector rods and into which said key blocks may be engaged, said recessed portions having right angle shoulders engageable with the key blocks to prevent further extension of the connector rods and having the tapered portions adapted to cam out the key blocks when the connector rods are forced inwards.

13. An unwinding machine, comprising a pair of spaced side supports for resting on a counter, table or the like and having semi-annular top edges, tubes mounted between said side supports for holding them fixedly relative to each other, end wall members extending forwards and rearwards and disposed outwards of the outer faces of said side supports, connector rods mounted on said end wall members and slidably engaging in said tubes for movably connecting the end wall members with said side supports, a U-shaped element centrally on the top of one of said end wall members, a U-shaped member centrally and swivelly mounted on the top of the other of said end wall members, a rod for supporting a roll of cloth rested across said U-shaped parts, a ball bearing fixedly mounted on said rod and removably engaged in a groove formed along the inner face of said U-shaped element, said U-shaped member having its inner face formed with a groove, and ball bearings mounted along said latter groove to provide a bearing for said rod.

14. An unwinding machine, comprising a pair of spaced side supports for resting on a counter, table or the like and having semi-annular top edges, tubes mounted between said side supports for holding them fixedly relative to each other, end wall members extending forwards and rearwards and disposed outwards of the outer faces of said side supports, connector rods mounted on said end wall members and slidably engaging in said tubes for movably connecting the end wall members with said side supports, a U-shaped element centrally on the top of one of said end wall members, a U-shaped member centrally and swivelly mounted on the top of the other of said end wall members, a rod for supporting a roll of cloth rested across said U-shaped parts, and ball bearings for said rod mounted on said U-shaped parts.
